TYPEWRITING MACHINE

Filed April 19, 1927

UNITED STATES PATENT OFFICE

JOSEPH PHELPS, OF NORTH CALDWELL, NEW JERSEY, ASSIGNOR TO REMINGTON TYPEWRITER COMPANY, OF ILION, NEW YORK, A CORPORATION OF NEW YORK

TYPEWRITING MACHINE

Application filed April 19, 1927. Serial No. 184,902.

My invention relates to typewriting and like machines and more particularly to means for counting the strokes of the printing keys and space key.

5 The invention is intended to accomplish some of the same general results as the construction disclosed in the patent to Clio B. Yaw, No. 1,012,785, dated Dec. 26, 1911, and in the application of Arthur W. Smith, Serial No. 622,715 filed March 5, 1923.

One of the objects of my invention is to provide an improved construction of the character described which may be readily applied as an attachment to Remington machines, models Nos. 12, 20, 21, 23, 30, 50 and to other model Remington machines, without modifying, or materially modifying, the structural features of said machine as they now exist.

20 To the above and other ends which will hereinafter appear, my invention consists in the features of construction, arrangements of parts and combinations of devices set forth in the following description and particularly 25 pointed out in the appended claim.

In the accompanying drawings, wherein like reference characters indicate corresponding parts in the different views,

Figure 1 is a fragmentary, top plan view 30 of the counter, together with the actuating connections and some of the associated parts of a No. 12 Remington typewriter common to a number of different models of such machines.

35 Figure 2 is an enlarged, detail transverse, sectional view taken on the line 2—2 of Fig. 4 and looking in the direction of the arrows at said line.

40 Figure 3 is an enlarged, detail, transverse, sectional view taken on the line 3—3 of Fig. 1 and looking in the direction of the arrows at said line.

45 Figure 4 is an enlarged, detail, fragmentary, fore-and-aft vertical sectional view

taken on the line 4—4 of Fig. 3 and looking in the direction of the arrows at said line.

I have shown only so much of a No. 12 Remington typewriter machine as is necessary to arrive at an understanding of my invention in its embodiment therein.

50 While the parts of the typewriter shown are common to several models of Remington machines, and the present invention may be readily incorporated therein without modifying, or materially modifying, the structural features thereof, it should be understood that the invention is not restricted to use in such machines but may be employed in typewriting or like machines generally, 55 wherever found available.

55 The usual power driven carriage, shown only in part in the drawings, includes end bars 1 and a rear cross bar 2 grooved to receive anti-friction rollers which likewise are received in the grooved face 3 of a fixed guide rail 4 secured to the top plate 5 of the machine. A pull band 6 is connected at one end to the usual spring drum (not shown) and at the other end to a bracket arm 7 secured 60 to the carriage. The carriage is advanced step-by-step in the direction of its letter feed movement, indicated by the arrow *a* in Fig. 1, by the power of the spring drum and under control of the usual escapement mechanism 65 which will now be described.

70 A yoke-like supporting bracket 8 is detachably secured by screws 9 to a member 9^a secured to the bottom of the top plate. This bracket has two arms 10 and 11, the arm 10 75 extending forward of the escapement wheel shaft 12 and having a bearing opening in which the forward reduced end 13 of the shaft is received. The arm 11 of the bracket extends around to the rear of the escapement 80 wheel shaft and has an opening in which a bearing sleeve 14 is seated and held in place by a set screw 15. The rear reduced end 16 of the shaft 12 receives a bearing in the sleeve 14. An escapement wheel carrier 17 is con- 85

nected by its hub to turn with the shaft 12 by two set screws 18, one of which is shown in Fig. 4. The annular escapement wheel 19 is secured to its carrier 17 by three screws 20, two of which are shown in Fig. 3. So far as the present invention is concerned the connected parts 17 and 19 may be regarded as one piece, which may be called the escapement wheel. A sleeve 21 loosely surrounds and receives a bearing on the shaft 12. One end of this sleeve is provided with a feed pinion 22, whereas the opposite end of the sleeve is provided with a combined backing ratchet and back spacing wheel 23. This wheel is shaped to form a housing in which is received a backing pawl 24 pivoted at 25 on the carrier 17 of the line spacing wheel. The engaging nose 26 of this pawl coacts with the inner corners 27 of the teeth 28 of the wheel 23, being normally held in such engagement by a wire spring 29 anchored at one end on a pin 30 carried by the escapement wheel and bearing at its opposite end in a depression in the pawl 24. The effect of this pawl and ratchet connection between the feed pinion 22 and the escapement wheel is to connect the two to turn together in one direction, and to permit the feed pinion 22 to be rotated in an opposite direction independently of the escapement wheel, as will hereinafter more clearly appear.

A feed rack 31 is secured by screws 32 to a feed rack carrier 33. Each of the rearwardly extending arms of the carrier is tapped to receive a screw 34 which at its outer reduced end is received in a bearing opening in a bracket arm 35 secured to the carriage. This provides a pivotal support for the rack carrier to enable the rack 31 to be lifted to disengage its teeth 36 (see Fig. 4) from meshing engagement with the teeth of the feed pinion 22, at which time the carriage is free from control of its escapement mechanism and may be moved in either direction in its line of travel. To thus lift the feed rack the rear end of the usual key controlled release lever 37 extends beneath the feed rack, as indicated in Fig. 1.

The usual normally engaged loose dog 38 and the fixed holding dog 39 coact with the escapement wheel (see Fig. 4) to advance it one tooth at each actuation of a printing key or the space key, and thus enable the carriage to advance a letter space distance. The usual automatically controlled detent 40 is employed to prevent a backward rotation of the escapement wheel.

As thus far described the construction is such as that commonly employed in different models of Remington machines, and it is one of the purposes of the present invention to combine with certain of the parts described the counter and counter-controlling means of the present invention without the necessity of modifying any of the structural features

of these existing machines, as will now appear.

I provide a supporting arm or member 41 bifurcated at its upper and lower ends and shaped to form a seat that will receive the supporting sleeve 14, so that the latter may provide a support on the bracket 8 for the supporting member 41. The arms of the upper bifurcated end of the supporting member are connected by a screw 42 by which they may be drawn together to firmly clamp said member to the sleeve 14. This supporting member is located between the bracket arm 11 and the escapement wheel and is held fixed while the escapement wheel turns relatively thereto. The lower bifurcated end of the supporting member 41 provides a slot in which a worm wheel 43 is received. Aligned transverse bearing openings extend through the supporting arms on opposite sides of the wheel 43 to provide a bearing for a short spindle 44 to which the wheel is connected. One end of this spindle is connected to a flexible shaft 45 which has its opposite end connected to the driving shaft of a Veeder counter 46 which in the present instance registers one unit on the register wheels 47 of the counter for each complete revolution of the shaft 45, although obviously this may be varied by the selection of a different Veeder counter which gives a different ratio. The flexible shaft 45 enables the Veeder counter to be mounted in any convenient position and with the axis of its register wheels disposed in any desired angular relation relatively to the axis of the escapement wheel and the driving wheel 43. The flexibility of the shaft 45 also enables it to bend and compensate for the different heights at which the counter and worm wheel 43 are arranged. In the present instance the counter is riveted at 48 to a sheet metal base or bracket plate 49, which is secured to the top plate 5 of the machine by screws 50 and 51, the screw 50 being a headed clamping screw, the stem of which passes through an opening in the plate 49 and clamps it in place. This is a screw which is substituted for that commonly employed to attach other parts to the bottom of the top plate of the machine, and performs such ordinary function in the present instance. The screw 51 is received in a cut-out 52 in an edge of the plate 49 to prevent the plate and counter carried thereby from turning on the screw 50 as a pivot. The screw 51 is also one usually employed in the machine for another purpose and performs its usual function in the machine as well as the additional function pointed out above.

Motion is transmitted from the worm wheel 43 through the flexible shaft 45 to the counter, and the worm wheel is actuated by means carried directly by the escapement wheel 19 and coacting directly with the worm wheel. Such means in the present instance comprise a

worm device, which, as shown may conveniently be formed from a single piece of sheet metal and includes an annular base portion 53 secured to the rear side of the escapement 5 wheel by the same screws 20 by which the escapement wheel is attached to its carrier 17. The annular base is arranged concentrically with the escapement wheel and at its outer edge has a rearwardly projecting flange 10 54 substantially cylindrical throughout most of its extent. The flange is split to provide an abrupt end 55 and an inwardly inclined, cam actuating device, or worm portion 56 which is severed from the base at 57. The flange 15 54 is received between the teeth of the worm wheel 43 and during the revolution of the escapement wheel the circular or cylindrical portion of the flange will travel idly through a space between two adjacent teeth of the 20 wheel 43, thereby offering no resistance to the escapement wheel and the feed of the carriage. When, however, the worm portion 56 of the flange reaches a tooth of the worm wheel, the worm will cause said wheel to be 25 gradually advanced by an easy camming motion a tooth space distance of the worm wheel. This occurs at each complete revolution of the escapement wheel. There are, in the present instance, sixteen teeth on the worm wheel 30 43, and fifteen teeth on the escapement wheel. Therefore, it will require sixteen revolutions of the escapement wheel to advance the wheel 43 one turn and to set up one unit on the counter. This requires two hundred and forty 35 strokes on the printing keys or the space key, since the escapement wheel can be advanced only under control of the feed dogs 38 and 39 and these are controlled only by the printing keys and the space key. This represents, 40 say, between four and five lines of writing with pica type in an "A" carriage machine, but lines are not the unit registered, but the actual work strokes on the keys, two hundred and forty such strokes being the unit of 45 registration employed in the present instance, and which forms the basis by which payment is made to the operator for piece work or bonus. Obviously, however, the intermediate 50 connections between the escapement wheel and counter may be varied at will to cause a registration on the counter once for a greater or less number of key strokes than is indicated above, but such number is preferred as it is regarded as standard. 55 It will be understood that the power of the usual spring drum moves the carriage and transmits motion to the escapement wheel and to the counter controlled thereby, so that none of the resistance due to actuating the 60 counter is exerted against the operator in actuating the keys. It will be seen, moreover, that the resistance to be overcome in actuating the worm wheel 43 and the parts controlled thereby to operate the counter is but 65 slight, adding but little resistance to the

spring drum which may be easily and effectively employed to actuate the counter. Such slight drag as may be exerted against the drum is but momentary in the present construction and is only exerted during the 70 action of the worm 56 on a tooth of the worm wheel 43. The worm 56 at all other times travels free of the worm wheel and the parts controlled thereby, such parts offering no resistance whatever at such times to the free 75 traveling movement of the escapement wheel or to the travel of the carriage.

In the modern forms of Remington machines hereinbefore referred to, not only does the yoke-like bracket arm 11 extend in the 80 rear of the escapement wheel and shaft, but the tabulator frame containing some five or more upright tabulator levers are also arranged directly in the rear of the escapement wheel and its shaft in certain of the models 85 referred to. It will be seen therefore, that there is no room at such point to make connection with means for transmitting motion from the escapement wheel shaft to the counter as in the construction disclosed in the 90 Yaw patent hereinbefore referred to. However, by my invention the counter and its actuating mechanism may be readily connected as a single unit, and in the nature of an attachment, to any of such machines without modifying the structural features as they 95 now exist.

The present construction has all of the additional advantages of the Yaw construction in that the register cannot be fraudulently 100 run up by the operator as many other of the counters of the prior art can be. Thus, it will be seen that by the present invention the counter can only be actuated by the finger 105 strokes on the keys, and that it would require as much work to run up the register without writing as would be required to produce a corresponding amount of work or written matter.

The construction of the present invention 110 consists of but few parts, which may be readily assembled without requiring a nice fitting. The construction is inexpensive to manufacture, easy to attach, is not liable to be damaged or broken and is highly efficient in use. 115

Various changes may be made in the construction, and parts thereof may be employed without others, without departing from my invention as it is defined in the accompanying 120 claim.

What I claim as new and desire to secure by Letters Patent, is:—

In a typewriting machine the combination with a carriage escapement wheel which turns only in one direction and only when the carriage is fed by the keys, and a support for the shaft of said wheel comprising a fixed sleeve in which said shaft is journaled, of a worm turning with said escapement wheel, a worm wheel operated by said worm, a sup- 125 130

port for said worm wheel consisting of a bracket having a hole which fits on said fixed sleeve by which sleeve said bracket is supported and to which it is clamped, a counter attached to the fixed frame-work of the machine at an angle inclined to the axis of said worm wheel, and a flexible shaft extending from said worm wheel to said counter and operating the latter.

¹⁰ Signed at the borough of Manhattan, city of New York, in the county of New York and State of New York this 18th day of April, A. D. 1927.

JOSEPH PHELPS.
